UNITED STATES PATENT OFFICE.

CHARLES N. LEONARD, OF INDIANAPOLIS, INDIANA, ASSIGNOR TO THE DRAKE & WOOD COMPANY, OF SAME PLACE.

SURGICAL CHAIR.

SPECIFICATION forming part of Letters Patent No. 472,372, dated April 5, 1892.

Application filed March 10, 1891. Serial No. 384,464. (No model.)

To all whom it may concern:

Be it known that I, CHARLES N. LEONARD, a citizen of the United States, residing at Indianapolis, in the county of Marion and State 5 of Indiana, have invented certain new and useful Improvements in Surgical Chairs, of which the following is a specification.

My said invention relates to various improvements in the construction and arrangement of the details of that class of chairs known as "surgical chairs," whereby such a chair is provided capable of all required adjustments, and which, while being of great durability and strength, and adapted to furnish a firm support in whatever position it 15 may be used, is at the same time of comparatively small cost, of great simplicity in structure, and easy and convenient of adjustment, as will be hereinafter more particularly described and claimed.

Referring to the accompanying drawings, which are made a part hereof, and on which similar letters of reference indicate similar parts, Figure 1 is a top or plan view of a chair constructed in accordance with my said invention, the back being shown in substantially a horizontal position and a portion of the right arm being broken away to more clearly show the parts beneath it; Fig. 2, a 25 side elevation of the chair in the same position with the stirrup attachment added; Fig. 3, a central vertical section on the dotted line 3 3 in Fig. 1, the back being shown in upright position and the foot-rest in elevated 35 position, other positions of the two parts being indicated by dotted lines; Fig. 4, a plan view of the base of the chair with the seat removed; Fig. 5, a view similar to Fig. 3, except that the back is in a reclining position, 40 the foot-rest down, and the seat tilted to a backwardly-inclined position; Fig. 6, a cross-section looking in the direction of the arrows from the dotted lines 6 6 in Figs. 3 and 5, the seat being shown in the "side-tilt" position, 45 the reverse position being indicated by dotted lines; Fig. 7, a detail cross-section looking in the direction of the arrows from the dotted line 7 7 in Fig. 3, showing the way in which the spring-pawl for holding the back 50 in adjustment are mounted; Fig. 8, a detail perspective view showing the rear side of the foot-rest and the mechanism thereto at-

tached; Fig. 9, a detail section looking in the direction of the arrows from the dotted line 9 9 in Fig. 8; Fig. 10, a detail perspective 55 view of a portion of Fig. 8; Fig. 11, a detail sectional view looking in the direction of the arrows from the dotted line 11 11 in Fig. 12; Fig. 12, a similar view looking in the direction of the arrows from the dotted line 12 12 60 in Fig. 11; Fig. 13, a detail plan view looking in the direction of the arrows from the dotted line 13 13 in Fig. 2; Fig. 14, a detail section looking in the direction of the arrows from the dotted line 14 14 in Fig. 13, and Fig. 15 a detail elevation looking, as indicated by 65 the arrows, from the dotted line 15 15 in Fig. 3.

In said drawings, the portions marked A represent the frame of the base or stool of the chair; B, the seat; C, the back; D, the foot-rest, and E the stirrup-bar.

The base A consists, preferably, of a rectangular frame supported on suitable legs or feet properly braced and framed together, substantially as shown; but, as will be readily 70 understood, may consist of any form or arrangement of frame-work found suitable. It has attached thereto those portions of the operating mechanism which require bearings thereon, and supports the seat on its top. This 75 mechanism will be particularly described hereinafter in connection with the description of the construction and operation of the parts connected therewith.

The seat B consists of a suitable frame and 80 is mounted on the base A to be adjusted in various positions thereon. Its front rests upon the front cross-bar A' of the base, which is formed with a high portion at its center to support said seat at the desired elevation 85 above the rest of the frame-work of the base, being tapered toward each end from said central point (see Fig. 12) to permit the seat to be rocked or tilted sidewise, as will be presently described. At a point between its center and rear edge, midway between its sides, is secured a downwardly-projecting stud b, with a ball-shaped end, which rests in the cup-shaped cavity or bearing in the top of the casting a, secured to the rear cross-bar of the 90 base A. These two rests furnish the main support for the seat when in a horizontal position, or the position shown in Figs. 1, 2, and 3. It will be understood, of course, that the 95

position of these parts might be reversed or another universal bearing substituted therefor without departing from my invention or avoiding my claims wherein the relative positions shown are specified.

To each side of the seat-frame, in line with the bearing b , is secured a downwardly-projecting ear b' , (see Fig. 6,) in which are provided bearings for the ends of the curved rack-bar B' , which ends are formed as journals and mounted in said bearings. Said rack-bar B' is curved downwardly and rests substantially against the inner face of the rear cross-bar of the base A . A roller or other suitable bearing a' is secured to said cross-bar at a point directly below the bearing between the parts a and b , under which roller the upper edge of said curved bar operates, said roller or bearing a' being formed with a recess or lip to engage the edge of said bar, thus operating to hold it steady and also prevent the seat from being lifted out of the bearing a when the chair or back is raised. A bearing a^2 is secured to one of the side pieces of the base A , and at a point between the center of the chair and the opposite side piece another bearing a^3 is secured to the rear cross-bar, and in said bearings a^2 and a^3 is mounted a shaft A^2 , provided with a worm-gear, as shown, (see Fig. 6,) which engages with the teeth on the central portion of the curved bar B' . On the outer end of said shaft a crank or hand-wheel A^3 is provided, by which said shaft may be turned, and through the various connections described operate to tilt the seat from side to side, as will be readily understood. By this arrangement any degree of side inclination may be easily secured and maintained without any lock or other support, the friction between the gears being sufficient to hold the parts in any position to which they are adjusted.

Near the front edge of the seat is secured a housing b^2 , provided with bearings in which the journals of a depending rack-bar B^2 are mounted. Said journal - bearings are arranged in line longitudinally of the chair with the rear bearing b , and the bar depending therefrom is provided with a series of notches in one of its sides, the ends of the portions between the notches being formed V-shaped, or tapered to a point. To the rear face of the front cross-bar A' of the base is secured a casing A^4 , through a vertical way in which said bar B^2 extends. In the rear wall of said casing is formed a perforation, through which a reciprocating catch-bar A^5 is arranged to slide, the catch a^5 of said bar being formed on its side adjacent to the bar B^2 , the point of said catch being formed wedge-shaped, and thus adapted to engage with the notches in the side of said bar B^2 . Said bar A^5 is normally held forward and its catch a^5 into engagement with the notches of said bar B^2 by means of a spring a^6 , mounted on a rod A^6 , running from a point directly under the bearing b to and through a projec-

tion on the side or edge of said bar A^5 , as shown, (see Figs. 5 and 11,) between which points said spring bears. Said bar A^5 may be withdrawn and its catch a^5 disengaged from the notches of said bar B^2 by means of a foot-lever A^7 , which is connected thereto by means of a rod a^7 , connected with a bell-crank lever a^8 , rigidly secured to the rock-shaft A^8 , the rear end of said bar being connected to the upper end of another bell-crank lever a^9 , also rigidly secured to said rock-shaft A^8 , which is mounted in a bearing on the side of the frame at its outer end and in a bearing A^9 , preferably formed in piece with the casting in which the bearing a^9 is formed (see Figs. 4 and 6) at its inner end. By this arrangement the front edge of the chair may be adjusted to and secured at the desired elevation and the "back tilt" of the seat provided for. The notches in the sides of the bar B^2 being formed with flared mouths and the catch a^5 on the bar A^5 being formed with a pointed end, the pressure upon the foot-lever A^7 being released, the spring a^6 will always operate to force said catch into engagement with the nearest notch and secure the chair in the adjusted position. The catch a^5 being formed on the side of the bar A^5 , the end of said bar may be extended a short distance beyond said catch and be formed of a size to fit the perforation or bearing in the casing A^4 , through which it operates, thus enabling the catch to be withdrawn without danger of removing said bar from its bearing, and at the same time afford it a smooth and straight edge to slide upon throughout its entire movement. A stop a^{11} is provided on the side piece of the frame A , against which the bell-crank lever a^8 is adapted to strike when the catch has been withdrawn from engagement with the notches of the bar B^2 , and thus limit its movement at the proper point. In each side of the casing A^4 a perforation a^{10} is provided, (see Fig. 11,) and rods A^{10} , with their rear ends secured in perforations near each end of the bar B^2 , (see Fig. 4,) are provided with hook-shaped forward ends, which are inserted or hooked into said perforations a^{10} , which, being larger than the rods, permit the hooks to be moved or twisted therein sufficiently to allow the free tilting of the seat. By means of nuts on the rear ends of said rods the two parts are or may be tightly drawn together, and a very secure and efficient brace and support for the seat and mechanism on which it is supported is thus provided, the rear portion of the seat being thus firmly secured to the forward portion of the base. By this arrangement, as will be readily understood, the seat may be not only easily and quickly tilted to the rear or side, and firmly supported in whatever position desired, but the rear and side tilt may both be secured at the same time, if desired, and the same firm and secure support is still afforded.

The back C is secured to the rear of the seat-frame work by hinges c , and is provided

with arms C', hinged to each of its sides at their rear ends and to a standard C² at their forward ends, said standards being in turn hinged to the side pieces of the seat-frame.

5 On the under side of each of said arms a toothed rack c' is secured. In suitable bearings at the rear edge of said seat is mounted a shaft C³, having rigidly secured to each end thereof fingers or pawls c³, formed to engage with said rack c' on the under side of the arm and hold said back in the desired position. Around said shaft C³ a spring c² is coiled, one end of which is secured to the seat-frame and the other end to the shaft, the tension 15 of the spring being so exerted as to tend to turn the shaft toward the back of the chair, and thus at all times keep the pawls in engagement with the rack c'. A small thumb-piece or projection is formed on the side of each of said pawls, by which they may be pushed down out of engagement with the rack when desired. The pawls being normally held against the rack at all times when the back is raised from a horizontal position, they catch 20 automatically in each successive notch of the racks, permitting the back to be released from the elevating-power at any time and held in substantially the position it occupied when released. At a suitable point on the rear of 25 each side of the chair-back is secured an ear c⁴ in a perforation, in which the upper ends of a brace C⁴ are mounted. Said brace C⁴ preferably consists of a rod bent to form a short horizontal part c⁵ in its center, which forms 30 its lower end, with its ends extending in a diagonal direction in each way from said center upwardly, the extreme ends being bent in to engage with the bearings provided therefor in the ears c⁴, and preferably hooked down 35 to make the engagement secure. A casting C⁵, in the form of a short horizontal bar with a branch extending upward and also downward from each end thereof, is mounted on the part c⁵ of the brace C⁴, the connection 40 being preferably made by passing the rod through transverse perforations in said upwardly-extending branches before its ends are connected to the chair-back. A hinge-joint 45 is thus formed in the brace, which consists of both parts, and this joint constitutes the leading distinction of my invention over other braces now in use. The lower branches of 50 said part C⁵ embrace the sides of a casting B³, secured to the rear corner of the seat and extending downward therefrom. A short vertical slot b³ is formed near the upper end of 55 said casting, with which studs c⁶, formed on the adjacent faces of the branches of the part C⁵, which embrace said casting B³, engage. 60 This engagement may be secured by forming the part C⁵ of malleable iron or similar material, which will permit said branches to be spread sufficiently to insert the studs in the slot, when they can be drawn together. As 65 will be readily understood, the part C⁵ may be of cast instead of malleable iron and a pin inserted through the several parts to se-

cure the connection, if preferred. On the lower end of the casting B³ are formed hook-shaped rests b⁴ and b⁵, into which the part c⁵ 70 is adapted to rest when the back is tilted to its extreme positions. In Fig. 3 said back is indicated in dotted lines in the position substantially in line with the seat, this being shown as the extreme limit of the backward 75 tilt, and the part c⁵ of the brace is shown as resting in the hook-shaped rest b⁵. In Fig. 5 the back is shown tilted to position so that the part c⁵ of the brace is given a bearing in the hook-shaped rest b⁴. Each of said hook-shaped rests is made so that when this part of the rod or brace is resting therein it will be caught under the points of the hook sufficiently to require that the brace shall be slightly elevated before they will become disengaged, the 85 slot b³ in the castings B³ being for the sole purpose of permitting said elevation. By this means the chair may be tilted forward from the position shown in Fig. 5 by lifting upon the back of the chair without disturbing the relative position of said seat and back. By means of this brace the chair-back is firmly supported in a horizontal position, which position brings the arms C' and pawls c³ to a 90 position so nearly parallel as to render the support afforded by said pawls inefficient. The rest b⁴ also enables a position to be secured intermediate that of the last two notches of the rack-bar c' with the consequent advantage. 95

The foot-rest D is hinged to the upper corner of the front edge of the seat-frame, and has a part D' hinged thereto, as shown. A rock-shaft D² is journaled centrally in the frame of the main part of the foot-rest, having a wing d, formed on one side thereof, in which is provided a series of notches. Said wing being formed at one side of the center of said shaft, its weight tends to at all times keep the notched edge down, a stop d' being 105 formed on the upper end of said shaft adapted to come in contact with a portion of the frame and limit its movement when it reaches that position where said notched wing will thus automatically engage the catch-bar. A 110 projection is also formed on said shaft, with which a rod d² is connected, said rod extending out to the edge of said foot-rest and being provided with an eye or suitable handle by which the operator is enabled to seize it to 115 rock said shaft to disengage said catch, when desired. A catch-bar or brake D³, formed of a bar bent into a form similar to the form of the rod C⁴, before described, with two diagonal sides and a straight portion connecting them, is 120 hinged at the upper ends of its sides to the lower corner of the front edge of the seat, the straight portion of the bar being arranged in close proximity to the under face of the foot-rest, and held in such relation by means of a 125 strap d³, fastened to the rear side of the frame with the straight part of the catch-bar resting on its upper surface, and thus adapted to slide and be supported thereon. With this part 130

of the catch-bar the notches of the pivoted wing d are adapted to engage when said wing is allowed by its own weight to turn down to the position shown in Figs. 8 and 9.

5 To each side of the frame a lever D^4 is pivoted, the inner end of which is connected by a link to the straight portion of the catch-bar, and the outer end of which is connected by a strap d^4 to a bolt or pin secured in the front 10 portion D' of said foot-rest. The joint between the levers D^4 and strap d^4 is of a loose character, to permit a slight motion in both directions required. The foot-rest being in the positions shown in Figs. 1, 2, 5, and 8, it is 15 only necessary in order to change it to the position shown in Fig. 3, to lift it upward on its hinges, when the notched wing d will slide over the catch-bar D^3 , which will engage with the successive notches and support said foot- 20 rest in whichever of the positions is desired, as indicated by dotted lines in Fig. 3. When raised to the limit, said catch-bar engages with the last notch and supports said foot-rest in a horizontal position, as indicated by 25 whole lines in said figure.

It will be understood, of course, that any number of notches may be formed in the wing d , and the adjustment of the foot-rest to an equal number of positions thus provided for.

30 While the foot-rest is being raised, the catch-bar being pivoted to the lower corner of the front of the chair-seat, its front draws back toward the rear of the foot-rest, which, through the levers D^4 and links d^4 , operates to gradually straighten out the part D' of the foot-rest until when the horizontal position is attained said part is in line and forms a continuous plane with the main portion D thereof.

The stirrup-bar E is provided with a down- 35 wardly-extending stud e near its rear end, adapted to be inserted in a socket d^7 on the rear side of the top edge of the foot-rest. Said socket is formed somewhat larger than said stud, as indicated in Fig. 14, in order to allow said bar to be adjusted vertically to various 40 positions. Behind said stud e the upper corner of the bar E is extended to form a lip or catch, which when said bar is swung into operative position engages under a pro- 45 jecting part b^3 , secured to the front edge of the seat in suitable position for the purpose. In placing said stirrup-bar in position said stud is inserted in the socket d^7 when the stirrup-bar is in position substantially at 50 right angles with the side of the chair, as indicated by dotted lines in Fig. 13, and is then swung around to the position indicated by whole lines, or any other position desired for use, the rear end catching under the projec- 55 tion b^3 and preventing said stirrup-bar from being inadvertently lifted out of its socket. Said stirrup-bar is supported from lateral movement by a brace E' , hinged to its side and formed in two parts, slotted and adapted 60 to slide upon each other, being secured together by a thumb-nut and screw e' , the other end being turned downwardly and loosely in-

serted in a socket d^8 on the rear side of the foot-rest, as shown. By this means the stirrup-bar is allowed to be adjusted sidewise, as 70 desired, and secured rigidly in the adjusted position. It is supported at the desired elevation by means of a brace E^2 , which is also formed in two parts, secured together by a thumb-nut e^2 and adapted to slide upon each other, as are the two parts of the brace E' . The lower end of said brace is formed with a suitable journal and is mounted in a suitable bearing d^9 , secured to the edge of the foot-rest, and the upper end is pivoted to a socket 80 E^3 , mounted and adapted to slide on said stirrup-bar, a set-screw e^3 being provided, by which it may be secured in the desired position. A leg-rest E^4 is also mounted on the stirrup iron or bar by means of a socket e^4 , secured thereto, as is the socket E^3 , said leg-rest being also vertically adjustable in its 85 socket, which is also adapted to turn on said bar, a set-screw e^5 being provided by which it is secured in the position desired. The 90 stirrup E^5 is also secured to said stirrup-bar in a manner similar to that specified for the leg-rest. By this arrangement the legs of the patient being operated upon can be secured in any desired position and the knees comfortably supported at the desired elevation. 95

By this construction and arrangement a chair is provided adapted to meet all of the varied needs of such a chair, it being adapted to be adjusted to every position desired with ease and celerity, while the mechanism is all of a simple and inexpensive character, but at the same time so arranged and secured to the respective parts as to support the chair in whatever position it is adjusted firmly and securely without danger of breakage or displacement of the parts, thus overcoming a fault in chairs of this character in common use, which frequently destroys their usefulness and interferes with their ready adjustment to the desired positions. 105

By adjusting the chair to the position shown in Figs. 1, 2, and 5, it is adapted for such uses as an operating-table is usually required for; or, as will be readily understood, if preferred, the chair-frame can be modified to the form of a table-top, or a regular table-top substituted for the seat-frame without departing from this invention, the same adjusting mechanism being equally applicable to the operation thereof, the use of such tables frequently requiring the adjustments provided for by said mechanism. 115

Having thus fully described my said invention, what I claim as new, and desire to secure by Letters Patent, is— 125

1. In a surgical chair, the combination of the base, the seat mounted on said base and supported thereon by a bearing located midway between the sides thereof, which bearing is formed to permit said seat to tilt in either direction and one part of which is secured to said base and the other part of which is secured to said seat, a cross-bar formed curved 130

or downwardly extended in its center, journaled at its ends in suitable bearings secured to the sides of the seat and arranged in line with said central bearing, and a rod journaled 5 in suitable bearings in the base and extending in and engaging with said central portion of the cross-bar, whereby the seat may be secured and operated, substantially as set forth.

2. In a surgical chair, the combination of 10 the base or stool, a socket secured on the rear cross-bar of said base or stool midway between the sides thereof, the seat mounted on said base, a ball-bearing secured to the underside thereof and arranged to rest in the socket on 15 the base, a bar formed with a downwardly extending or curved center journaled at its ends in suitable bearings secured to each side of said seat in line with said ball-bearing, a bearing secured to the base-frame and engaging 20 with the upper edge of said curved bar, which slides thereunder, a screw-rod rigidly mounted in suitable bearings in said base and engaging with said downwardly curved or extended portion of said bar, whereby said 25 seat is afforded a rigid support and at the same time may be tilted in either direction, a rack-bar depending from the front edge of said seat, and a pawl mounted on the base, adapted to engage therewith, substantially as 30 set forth.

3. In a surgical chair, the combination of the base, a seat supported by suitable bearings on said base, the rear central bearing of which is a ball-and-socket joint or bearing, 35 and the front central bearing of which is a rack-bar journaled in an appropriate housing secured to said seat and depending therefrom to engage with a suitable retaining-catch on the base, the journals of said rack-bar being 40 substantially in line with said rear bearing, and an additional rear support and operating device consisting of a bar secured at its ends to the sides of the seat-frame by a hinge or pivotal connection arranged substantially in 45 line with said ball-and-socket bearing, which bar has a downwardly depending portion connected with a screw-rod appropriately mounted in the base-frame, whereby said seat is secured in or operated to the desired trans- 50 verse adjustment, substantially as shown and described.

4. In a surgical chair, the combination of the base the front rail of which is formed elevated in its center to form a rest for the seat-frame when in a horizontal position, a socket secured to the rear rail of said base-frame substantially midway thereof, said seat-frame mounted on said base and provided with a ball-bearing which rests in said socket of the 55 base-frame, a rack-bar depending from the front portion of said seat-frame, to which it is hinged on journals in line with the other supports, a sliding pawl suitably mounted on said base and arranged to engage with said rack-bar, a curved bar B', journaled at its ends in suitable bearings on the sides of said seat-frame, which bearings are arranged in line

with the central rear ball-and-socket bearing, and a screw-shaft journaled in suitable bearings on the base-frame and connected with 70 said curved bar, substantially as set forth.

5. In a surgical chair, the combination of the base, the seat mounted thereon, provided with a support for a brace, the back hinged to the rear edge of said seat, and a jointed 75 brace, one end of which is connected with said back and the other end of which is connected with said seat, the joint thereof forming a shoulder in said brace at that point where, when the back is inclined to a horizontal or 80 substantially horizontal position, it will rest upon said support on the seat, substantially as set forth.

6. In a surgical chair, the combination of the base, the seat mounted thereon and provided with the casting B³, having hook-shaped rests b⁴ and b⁵, the back hinged to the rear edge of said seat, and the brace C⁴, the upper end of which is secured to said back and the lower end of which is secured in a vertical slot 90 in said casting, a joint formed in said brace and having a shoulder which will rest in one of the rests b⁴ or b⁵ when said back is turned down, substantially as described, and for the purposes specified. 95

7. In a surgical chair, the combination of the base, the seat mounted thereon, the back hinged to the rear edge of said seat, the brace C⁴, connected to said back at one end and by a hinge connection to the casting C⁵ at the 100 lower end, said casting C⁵ being formed to embrace the casting B³, secured to the rear edge of the chair and formed with projecting points c⁶ on its lower ends, which are mounted in the slot b³ in said casting, and rests formed 105 in said casting, wherein the straight or horizontal portion c⁵ of said brace C⁴ is adapted to rest when the back is turned down, substantially as described, and for the purposes specified. 110

8. In a surgical chair, the combination of the base, the seat mounted thereon, and a foot-rest hinged to the upper corner of the front edge of said seat and formed in two parts D and D', hinged together, the rock-shaft D², 115 carrying the notched wing d on one side, mounted in bearings in the part D, and the catch-bar D³, hinged to the lower corner of the front edge of said seat and formed with a portion arranged to engage the notches of said 120 wing d, substantially as set forth.

9. In a surgical chair, the combination of the base, the seat mounted thereon, the foot-rest formed of the two parts D and D', hinged together and hinged to the upper corner of 125 the front edge of said seat, the rock-shaft D², journaled in suitable bearings in said part D, extending longitudinally thereof and provided with the notched wing d on one side, the catch-bar D³, hinged to the lower corner 130 of the front edge of said seat and arranged to engage the notches of said wing as it drops to the proper position by its own gravity, and the levers D⁴, pivoted to the sides of the frame

of the part D and connected to the front end of said catch-bar at one end and to links d^4 at the other end, said links d^4 being in turn connected to the part D' of the foot-rest, substantially as described, and for the purposes specified.

10. In a surgical chair, the combination of the base, the seat, the foot-rest hinged to the upper corner of the front of said seat, the rock-shaft D², provided with the notched wing d on one side and with the stop d' , arranged to limit the movement of said shaft in one direction, the rod d^2 , connected with said rock-shaft and leading to a position convenient to 15 reach, whereby said shaft may be operated in the direction to disengage said notches from the catch-bar, and said catch-bar D³, hinged to the lower corner of the front edge of said seat and arranged to engage said notches, substantially as set forth.

11. The combination, with a surgical chair, of a stirrup-iron extending out from its front edge, a stirrup adjustably secured to its outer end to swing thereon or be adjusted longitudinally thereof, and a leg-rest also mounted on 20

said stirrup-iron between the chair and said stirrup and secured thereto to be adjusted longitudinally or vertically or to swing thereon, substantially as set forth.

12. In a surgical chair, the combination of 30 the base, the seat mounted on said base, the foot-rest secured to the front of said seat, a bar projecting from the front of said chair, and a leg-rest mounted to be vertically adjusted on said bar and also to be adjusted longitudinally thereof, substantially as set forth.

13. In a surgical chair, the combination of 35 the base, the seat mounted on said base, the foot-rest secured to the front of said seat, a bar projecting out from the front of said chair, and a leg-rest mounted to swing and be adjusted vertically and longitudinally on said bar, substantially as set forth.

In witness whereof I have hereunto set my hand and seal, at Indianapolis, Indiana, this 45

5th day of March, A. D. 1891.

CHARLES N. LEONARD. [L. S.]
